UNITED STATES PATENT OFFICE.

CIPRIANO ANDRADE, JR., OF NEW YORK, N. Y.

WINDLASS.

Application filed October 7, 1927. Serial No. 224,542.

My invention relates to a windlass of simple form and construction, and the objects of my invention are; first to provide a form of windlass which will rotate in one direction and not in the other; second to have said rotation in one direction and not in the other handled by a roller; third to have said rotation in one direction and not in the other handled by a flexible band.

10 I attain these objects by the mechanism illustrated in the accompanying drawings, in which:

Fig. 1 is a sectional side elevation of my device on the line 1—1 of Fig. 2; Fig. 2 is a downward view of a portion of my device on the line 2—2 of Fig. 1 with a portion thereof in dotted lines; Fig. 3 is a sectional view of a portion of my device on the line 3—3 of Fig. 1; Fig. 4 is a side view of one of my rollers; Fig. 5 is an upward view of the part C³ thereof; and Fig. 6 is a downward view of the part D.

Similar letters and numerals refer to similar parts throughout the several views.

25 A is a canvas belting; A¹ is an end part of A, and fastened to B by any mechanical means; A² is the other end part of A and fastened to B¹ by any mechanical means; B is a handle bar holder; B¹ is another portion of B; B² is the end of B¹, which holds the end A² of canvas belting A by any mechanical means; B³ is a handle bar; C is the circular sheave to hold rope; C¹ is a flat upper circular surface of C to prevent B¹ from moving upward; C² are recesses in C to hold rollers R, each recess C² holds a roller R, but in Figs. 1 and 5 the rollers are not shown, in order to make the other parts visible; C³ is a flat bottom circular surface of C; C⁴ are circular outer surfaces of C, adapted to hold end B² either in locking or rotatable position; C⁵ is the inner circular surface of C; C⁶ is another circular outer surface of C, inward from both C⁴, adapted to hold A either in locking or rotatable position; C⁷ is a flat lower circular surface of C to prevent B¹ from moving downward; D is a flat circular bed plate; D² are recesses in D adapted to either hold or release rollers R; D³ is the lower surface of D²; D⁴ are screw holes in D to hold screws K; E is an outer circular element, to hold C from moving up or sideways, but permitting it to rotate; and D⁵ are holes to hold screws through E, D and the deck under D, thus holding D and E in immovable position.

It will be understood that where my device is used for a linked chain, the usual whelps can be placed on the outer surface of circular sheave C to hold said linked chain, as shown for example in element U Fig. 1 of my issued Patent No. 970,597. Or if desired my device could be arranged to carry both a rope and a linked chain on circular sheave C as is well known in the art.

65 The operation of my device is as follows:

The function of my device is to rotate in one direction, but not in the other. For example the rotation can be clockwise. This clockwise rotation is accomplished by pulling 70 the handle bar B³ clockwise, whereupon the two ends A¹ and A² of canvas belting A are brought closer together, which forces canvas belting A tightly against the surface C⁶ of circular sheave C, and at the same time it 75 locks the end B² of handle bar holder B against the two surfaces C⁴ of said circular sheave C, the result being that said circular sheave C is thus forced to rotate clockwise, and thus pull inward any rope or chain fastened to said circular sheave C. During this 80 clockwise rotation of circular sheave C, it will be noted from Fig. 3, that the roller R which drops down from C² into D², works up on surface D³, without any locking. But the 85 moment that the handle bar B³ is started back anticlockwise, it puts the two ends A¹ and A² of canvas belting A further apart from each other, which permits canvas belting A to loosen from the surface C⁶, and at the same 90 time it releases the pressure of B² against the two surfaces C⁴, which permits the canvas belting A and the handle bar holder B to move back anticlockwise over the surfaces C⁴ and C⁶. At the same time, it becomes impossible for the circular sheave C to move 95 anticlockwise, because as shown in Fig. 3 hereof, the roller R becomes locked on the left hand side of D³ in recess D², and also locked on the right hand side of recess C².

100 It will of course be understood that the function of canvas belting A and handle bar holder B could be also secured by eliminating the surfaces C⁴, and making surface C⁶ all the way from C¹ to C⁷, in which case the same 105 result would be had of bringing the two ends A¹ and A² closer together when handle bar holder B is moved clockwise, thus locking A on C⁶; and also when handle bar holder B is moved anticlockwise, it would put the two 110 ends A¹ and A² further apart, thus releasing the locking of A on C⁶.

It will be noted herein, that the use of the rollers R in all the recesses C² of Fig. 5 hereof, are very much simpler in construction than the pawls N with trunnions Z, which fit 5 into outward holes in recesses K, see Figs. 4 and 6 of my said previous Patent 970,597.

It will be understood also that any mechanical equivalent of the canvas belting A could be used; for example instead of canvas, 10 a flexible band of metal or any other mechanical equivalent of element A herein could be used.

It will be understood that the handle bar holder B could be made integral with the 15 handle bar B³, which of course would be a mechanical equivalent of these parts. The only purpose of having these two parts B and B³ is for convenience in taking out the long handle bar B³ when it is not in use, as is well 20 known in the art. It will therefore be understood that in the claims herein the words "handle bar" will apply to the two connected parts B and B³, or to the mechanical equivalent thereof, of B and B³ being actually integral with one another.

It will further be noted that elements C, C⁴, 25 C⁶, C⁷, A, A¹, A², B, B¹, B² and B³ could be

placed at the top of circular sheave C, instead of at the bottom of circular sheave C, with exactly the same function as herein stated. 30

I claim:

1. In a windlass; a circular sheave; a recess at the bottom of said circular sheave; a roller adapted to be fully contained in, or partly dropped down from, said recess; a bed plate in contact with said circular sheave, said circular sheave being rotatable over said bed plate; and a recess at the upper surface of said bed plate, said recess being adapted to lock said roller in one direction, and to let 40 said roller move freely in the other direction.

2. In a windlass; a circular sheave; a flexible band on the outer surface of said circular sheave; a recess in said circular sheave; a roller adapted to be fully contained in, or partly dropped down from said recess; a bed plate in contact with said circular sheave and rotatable therewith; and a recess at the upper surface of said bed plate, said recess being adapted 45 to lock said roller in one direction, and to let said roller move freely in the other direction. 50
